Patented Feb. 2, 1915.

UNITED STATES PATENT OFFICE.

DENNIS JOSEPH O'BRIEN, OF SAN FRANCISCO, CALIFORNIA, ASSIGNOR, BY MESNE ASSIGNMENTS, TO STRAIGHT FILAMENT LAMP COMPANY, A CORPORATION OF NEW YORK.

REFLECTOR.

1,127,082.

Specification of Letters Patent.

Patented Feb. 2, 1915.

Application filed December 30, 1904, Serial No. 239,012. Renewed September 7, 1912. Serial No. 719,161.

To all whom it may concern:

Be it known that I, DENNIS JOSEPH O'BRIEN, a citizen of the United States of America, and a resident of the city and county of San Francisco, in the State of California, have invented a new and useful Reflector, of which the following is a specification, reference being had therein to the accompanying drawing.

This invention is a sectional reflector, designed for use chiefly in connection with an incandescent electric tube-lamp which is subject matter for a separate patent, and the construction of which will not be herein set forth, except in so much as it directly affects the principle of the invention now under consideration. Other reflectors of similar type have been invented and patented by me or made the subject-matter of additional Letters Patent, and they have proved useful and successful, being adapted, in connection with the tube-lamps, for lighting stores, offices, halls, theaters, and all the various rooms and apartments of a building, as well as for street lighting and as headlights; in short, they have been employed with reasonable success wherever it is possible to use an incandescent electric lamp. But experience and careful study have pointed out certain advantages which may be obtained by additions and changes in the construction, especially in the manner of attaching the reflector to a fixture or chandelier, and in the connecting means provided for placing the lamp with which it is used in an electric circuit, and for firmly holding the lamp in a position parallel to each of the reflecting sections.

It is, therefore, the object of this invention to provide a reflector which shall combine all the good features and qualities of the previously invented forms with new and advantageous properties, and shall, without generating undue heat, multiply the rays of light produced by the lamp, be capable of immediate and safe attachment to or removal from a fixture or chandelier, allow the lamp to be quickly placed in or out of circuit without danger of shock to the person handling it, present a neat and pleasing appearance, and be durable and inexpensive.

In the accompanying drawing, Figure 1 is a sectional side elevation of one form of this improved reflector with a tube-lamp, of the kind above referred to, fitted into it. Fig. 2 is a cross section on the line $x-x$ of

Fig. 1, looking in the direction indicated by the arrow. Fig. 3 is an end view of a modified form of the reflector, the lamp being removed. Fig. 4 is a partly sectioned side elevation of the modified form of the reflector shown in Fig. 3. Fig. 5 is a sectional elevation of one of two socket-pieces used at the ends of the reflector. Fig. 6 is a similar view of the socket-piece, looking at right angles to Fig. 5. Figs. 7 and 8 are plan views respectively showing the bottom and top of the socket-piece. Figs. 9 and 10 are respectively a plan and an edge view of a nut placed in the socket-piece when used on the reflector shown in Figs. 1 and 2.

The lamp mentioned above, in so far as its construction relates to the present invention, comprises a glass tube or envelop 1, whose sides are straight and parallel to a straight-line filament 2, inclosed in the tube and held centrally therein by angular conductors 3, to which the ends of the filament are respectively anchored and which have their terminals sealed in and protruding through one side of the tube. A vacuum is, of course, created in the tube, and means adapting the lamp for connection in an electric circuit are provided in the form of metallic caps or bells 4, suitably soldered to the terminals of the anchor conductors 3 and cemented over the points on the outside of the tube where they protrude. From its shape, this lamp may be properly referred to as a tube or tubular lamp. It is a satisfactory form of incandescent lamp, being easily connected in a circuit, adapted to a great variety of uses, and capable of giving a powerful light. But though the present invention was designed to be used principally with this form of lamp and though it is described in such a connection herein, the right is, nevertheless, reserved to its use in all possible connections to which it is adapted, as well as to modifications in the form of its several parts.

This improved reflector is made up of a changeable number of substantially plane sections 5, which may be of transparent glass covered on the back with an amalgam, or of "white-glass", porcelain, or other suitable material. Although any desired number of these sections can be used, it is preferable to employ an odd number, and to make them of even width, so that the central section will be directly under the tube-lamp. These sections, whatever their

size and number, are placed edge to edge in an arc of a circle, each being tangential to the arc. They are held in this position by means of a segmental casing or frame 6, 5 of brass, tin, iron, or other sheet-metal adaptable to the purpose. The longitudinal edges 7 of this casing are bent in, over the adjacent edges of the outermost sections 5, as shown in Figs. 2 and 4, and upon the 10 ends of the casing are soldered strips 8 of the same metal, which extend back upon the ends of the sections, and hold them firmly in place. All the sections in the 15 construction illustrated in Figs. 3 and 4 are uniform in length and thus come under the edges 7 and strips 8, but in the form of the invention represented in Figs. 1 and 2 the strips 8 are made narrower and the central section 9 is shortened at both ends. 20 In order to have suitable places on the casing 6 where to apply the means provided in this form of the invention for holding the reflector to the fittings that connect it with the chandelier or other fixture. 25 The casing is reinforced in such places by extra thicknesses of sheet-metal, as 10, which are soldered upon the inside of the casing, one at each end. The inner ends of these metal pieces or plates 10 are slightly offset 30 and bent upon the ends of the short central section 9, which they firmly engage and keep in place.

In order to secure proper connection of the lamp in the electric circuit, and between 35 the lamp and the reflector, novel devices are employed, which from their shape and operation, may be termed removable socket-pieces and are herein designated by 11. Two of these socket-pieces are provided, one near 40 each end of the inside of the body of the reflector, at points which will be directly opposite the caps or bells 4 on the tube-lamp with which the reflector is to be used. The construction of each of the socket-pieces 11 is the same, each consisting, as best seen in 45 Figs. 5 to 8, of a substantially cylindrical receptacle, made preferably of porcelain or other good insulating material, and divided into two nearly equal parts by a partition 50 12, having a central aperture 13, of sufficient size to permit a wire to pass through. These socket-pieces 11 may be applied in various ways, of which two are illustrated herein, and they discharge several functions, as will 55 presently be described.

As above stated with reference to Figs. 1 and 2, special means are provided in the construction there shown, for holding the reflector to the fittings which connect it with 60 the chandelier or other fixture. The fittings referred to comprise a couple of tubes 14 and 15, held in line together by a spherical coupling 16 and having similar couplings 17 and 18 at their outer ends, the latter carrying 65 plugs 19 and 20 also formed with globu-

lar ends, and all spherical or globular members being in the line or plane of the tubing. The central coupling 16 is made with a flange 21, turned upward or away from the reflector and having a screw-threaded extension 22 (Fig. 2), adapting it for attachment to a similar, though somewhat larger, superimposed coupling 23 (Fig. 1), which is connected, preferably in the back, to an arm of a chandelier or other fixture (such, for instance, as is shown at 24 in Fig. 3), so that the line of tubing and couplings will be suspended at right angles to the arm. The end-couplings 17 and 18 have like flanges 25 and 26, but the latter are turned downward or toward the back of the reflector and each receives one end of a shouldered nipple 27, the other end of which passes freely through suitable holes made in the corresponding end of the casing 6 and in the plate 10 inside the same, the shoulder 28 of the nipple resting upon the casing. The nipple is externally screw-threaded on both ends, first for connection to either coupling flange on the back of the reflector, and secondly for similar engagement with one of the socket-pieces 11, within the reflector. One end of each socket-piece is furnished with a nut 29 for thus engaging the nipple. This nut is detailed at Figs. 9 and 10 and is also seen in Figs. 1, 5, 6, and 8. It is provided on opposite sides with obliquely-projecting lugs 30, which enter corresponding grooves 31, in the inner walls of the socket-piece, and thence are forced outward, by a spreading tool, into angular recesses formed, as at 32, beyond the inner ends of the grooves. The lugs are firmly set in these recesses, so that the nut becomes fixed in its socket, and provision is thereby made of an internal, well-fitting and durable, metallic screw-thread in the socket-piece wherewith to engage the end of the nipple that passes and is protruding through the casing of the reflector. The end of the socket having the nut is made to abut against the reinforcing plate 10 of the casing, as shown at the left end of Fig. 1, and to press the casing upon the shoulder of the nipple on the opposite side thereof, as it is being screwed up on the nipple. The combined socket-piece and shouldered nipple therefore coöperate in holding up their respective end of the reflector firmly to its fittings, that is to say, to the suspended line of tubing and couplings, which, in the form of the invention now being considered, extends parallel to the central line of the reflector, throughout the length thereof, but connects therewith only at the ends, by means of the end-couplings 17 and 18 and the nipple and socket respectively pertaining to each of these end-couplings, as hereinbefore stated. By following this construction, the reflector is made entirely sepa- 120

rate from the fittings and its application thereto is simple and convenient as well as secure.

The aforesaid fittings, it will be seen upon referring to Figs. 1 and 2, inclose the wires, as 33 and 34, that convey the electric current to the terminals of the tube-lamp, the wires proceeding from the arm of the chandelier or fixture and its coupling 23, into the coupling 16 thereunder, thence separating and running one through each of the tubes 14 and 15 and their respective end-couplings 17 and 18, down the nipples 27 in these end-couplings, directly into the socket-pieces 11, across the apertured partition 12 of each socket-piece, and into bushings 35, one of which is provided in the end of each socket-piece that is remote from the body of the reflector, and in which the contact ends of the wires are caught and stayed, each by a screw 36, passing through the side of the respective socket-piece and bushing and between leaf springs 37 therein, a pair of the latter being provided for, and adapted each 25 to receive, one of the caps or bells 4 on the side of the lamp. The inner ends of each pair of springs 37 are bent outwardly and held between the bushing 35 and the partition 12 above it. Within the body of the 30 bushing, these springs are slightly curved outwardly to let in between them the screw 36, which spreads them apart and against opposite walls of the bushing. The other ends of the same springs lie completely outside the bushing, facing each other, and are slightly broadened and hollowed to form a cup-like receptacle, to receive and hold either cap or bell 4 on the lamp that is pushed into the same. The springs, bushings, and screws are, by preference, all made of brass, or other metal that is a good conductor of electricity, the screws being employed, as suggested in the lower part of Fig. 6, for pressing bared portions of the 45 current-carrying wires against the inner walls of the bushings and causing the current to be transmitted through the latter to the pairs of springs and the lamp's terminals. See also Figs. 1 and 5. As will be 50 noted, the screw 36, in each instance, serves to maintain the bushing in proper position within the socket-piece, to hold up the leaf springs at a suitable height therein, to keep these springs in full contact with the bushing, and to make (or break) contact with the wires of the electric circuit. This screw is most conveniently reached from the end of the reflector, and therefore is placed on the side of the socket-piece that will normally be turned toward the end, as shown in Fig. 1 (and also in Fig. 3). The leaf springs, between which the screw passes, are likewise best located when turned toward the sides of the reflector, that is, edgewise relatively to the axis of the tube-lamp

placed therein in parallelism with the several reflective sections.

In the modified construction represented by Figs. 3 and 4, the wire-carrying fittings consist simply of a three-sided sheet-metal conduit 38 soldered directly upon the back of the casing 6, and a similarly soldered nipple 39 having a broad base within the conduit and an externally-threaded upper portion passing through the middle thereof, 70 this portion of the nipple being adapted for engagement with the central coupling 23 connected to the arm 24, both before mentioned. The wires, 33 and 34, pass from the coupling 23 into the nipple 39, and diverging are led through opposite holes in the base of the nipple, and out of the conduit, one of the wires passing out of each end thereof and thence into the adjacent socket-piece 11 through a small hole 40, which is 80 provided just above the partition 12, in the same side of the socket-piece as the hole for the wire-retaining screw 36. See Figs. 3, 4, 5, 6. The hole 40, it will be observed, is not used in the form of construction illustrated 90 in Figs. 1 and 2 and hence was not mentioned in connection therewith, though for the sake of convenience, it is provided in all the socket-pieces, to adapt them to either form of the invention. After passing 95 through the hole 40, the wire is passed through the opening 13 in the partition 12, along a sloping portion 41 thereof, and down between the springs 37, into the bushing 35, where the contact end of the wire is 100 engaged by the screw 36, in the manner hereinbefore explained. The fittings being substantially integral with the reflector in this modified form of the invention, the socket-pieces 11 are not connected thereto 105 by shouldered nipples and lugged nuts as in the other construction, but are merely held up to the strips 8 of the casing 6, each by a pair of angular sheet-metal braces or brackets 42, soldered to the respective strip, 110 and by a rivet 43, passed through and across both the braces or brackets and the socket-piece, all as shown in the said Figs. 3 and 4.

Both the herein described forms of the invention have the same means for holding the tube-lamp in a proper parallel position relatively to the several sections of the reflector and with its caps or bells 4 pressed between the outer ends of the leaf-springs 37 of the socket-pieces 11. The holding 115 means, as shown in Figs. 1 to 4, consists of two spring-clamps 44, each made of a single wire bent in the middle so as to form a narrow neck portion and two arms diverging therefrom but curving toward each other and long enough to receive between them a little more than half the circumference of the tube-lamp. One of these clamps is employed in connection with each socket-piece, and becomes a functionally integral, 120 125 130

though detachable, part thereof by having its neck portion passed up through a slot 45 in a lateral projection 46 of the socket-piece and retained thereabove by a ring or link 47, which is loose and cut, as at 48, to allow it to be opened for engagement with or disengagement from the said neck portion. See Figs. 6 and 7 in addition to Figs. 1 to 4. The wire from which the clamp is made has such resiliency that its two arms tend to spread outward, at the point of divergence from the neck, against the sides of the slot 45, while the slot maintains the arms close enough to each other to cause them to take a good hold of the lamp, when it is pushed in between them and placed in the electric circuit. Provision is thus made at once to keep the clamp and the lamp both firmly in place, and the means utilized therefor, it is thought, could hardly be simpler or cheaper or of easier application, no soldering or riveting being necessary. The projection 46 is located on the side of the socket-piece opposite to that in which the wire-retaining screw 36 is driven, so that the clamp carried thereby is fully insulated, and when both socket-pieces are in their respective positions on the inside of the reflector, the two projections thereto appertaining lie inward or facing each other and their clamps embrace the lamp at suitable distances from its extremities. The direction of the slots 45 is such that, the socket-pieces having been centered, the slots and the arms of the clamps therein will extend transversely of the body of the reflector, and the lamp, placed in these arms with its caps 4 in the cup-like receiver of the leaf springs 37, will be and remain truly parallel to the reflecting sections and normally in circuit.

To hold the lamp more securely between the embracing arms of the clamps 44 and preclude any possibility of its getting out of adjustment and failing in its electrical connections, one end of the wire forming each clamp is turned outward and back to make a loop 49, while the other end thereof is similarly bent to provide a hook 50, and a light spiral spring 51 is stretched across the lamp, with its ends respectively secured to the said loop and hook. See Figs. 1, 2, and 3. Each end of the lamp is thus provided with an encircling spring and all danger of the lamp being jarred out of its proper position is eliminated.

What I claim, and desire to secure by Letters Patent of the United States, is—

1. A reflector for substantially tubular electric lamps, comprising a segmental casing with a series of substantially parallel rectangular reflective surfaces arranged longitudinally edge to edge in an arc of a circle therein, means for holding the lamp in parallelism with the several reflective sur-

faces, a couple of tubes in the rear of the casing, spherical couplings joining the ends of the casing to said tubes and holding the tubes end to end and parallel to the axial lines of the reflector and lamp, a similar coupling intermediate the tubing to hang the same from the arm of a chandelier or fixture, and plugs on the end-couplings having globular outer ends in line with the tubing and couplings. 75

2. A reflector for a substantially tubular electric lamp, comprising an odd number of substantially parallel sections of uniform width and length, except the central section which is shortened at both ends, a casing therefor, means for binding the sections together and reinforcing the casing opposite the ends of the short section, suspending means in the back of the casing, socket-pieces located at the ends of said shortened section, and means for holding said socket-pieces to the casing and the latter to the suspending means by screw-thread connection. 80 85

3. A segmental reflector for a substantially tubular electric lamp, comprising a number of sections substantially parallel to the lamp, the central section being shortened at both ends, a casing therefor having its longitudinal edges turned inwardly over the outermost sections and also having end strips extending across all sections but the central one, reinforcing plates on the inside of the casing with offsets bent upon the ends of said central section, insulating socket-pieces adapted for connection with the lamp's terminals and abutting against said reinforcing plates, nuts fixed in said socket-pieces, a line of tubing provided with suitable suspending means, and shouldered nipples passed through the casing and its reinforcing plates and bearing on the back of the casing, said nipples engaging the ends of the tubing and the nuts in the socket-pieces and thus holding the back of the reflector to the tubing and the socket-pieces to the inside of the reflector. 90 95 100 105

4. A reflector for substantially tubular electric lamps, comprising any desirable number of substantially parallel sections, a casing for the same, insulating socket-pieces within the ends of said casing, each socket-piece being provided with an internal screw-thread, tubing, nipples secured in said tubing and connecting it with the reflector by being passed through the back of the casing and thence engaging the socket-pieces by their respective screw-threads, feed wires passing through the tubing, the nipples, and the socket-pieces to the lamp's terminals, and a wire-retaining screw in one side of each socket-piece. 110 115 120 125

5. A reflector for substantially tubular electric lamps, comprising longitudinally 130

- disposed reflective surfaces substantially parallel to one another and to the axis of the lamp, insulating socket-pieces secured on a central line therein and provided each with a slot running transversely with relation to said surfaces, and oppositely located clamps rigidly held in the slots of said socket-pieces and having arms spread outward also transversely of said reflector, the said clamps being thereby adapted to embrace the lamp crosswise at suitable intervals apart and maintain it in correct position centrally and longitudinally of the reflector and in parallelism with its several reflective surfaces.
5. In combination with a reflector and a lamp having outwardly projecting conductors connected to the filament ends and located one at each end and on the side of the lamp, a socket at each end of the reflector, means projecting outwardly from each socket to engage the lamp conductors, and separate means projecting outwardly from each socket to engage and support the lamp.
10. In combination with a reflector and a lamp having outwardly projecting conductors connected to the filament ends and located one at each end and on the side of the lamp, a socket at each end of the reflector, means projecting outwardly from each socket to engage the lamp conductors, a pair of spring clamps carried by each socket to engage on opposite sides of the lamp, and a coil spring connected at its ends to each pair of said clamps to extend transversely 30 across and to engage the outer arc of the lamp that is located between said clamps.
15. In combination with a reflector and a lamp carried thereby having lateral sockets connected with the filament at opposite ends, a combined support and wire carrier for the reflector consisting of a central transverse hollow element through which both of the circuit wires extend, and a conduit for each wire leading from said element, the outer ends thereof terminating in said sockets near the reflector ends.
20. In combination with a reflector and a lamp carried thereby having lateral conductors, one at each end thereof, a combined wire carrier and support for the reflector consisting of a longitudinal hollow element on the back of the reflector, hollow means to connect the ends of said element to the reflector, and a transverse hollow coupling secured to said element, the wires leading through the coupling, the hollow element, and the hollow means to engage with said conductors.
25. In combination with a reflector, and a lamp carried thereby having lateral socket connected with its filament at opposite ends, a combined support and wire carrier for the reflector consisting of a hollow conduit of substantially the reflector's length having a central inlet for both circuit wires and an outlet at each end for the respective wires, leading the latter into said sockets at the opposite ends of the reflector.
30. In combination with a reflector and a lamp having a lateral conductor at each end, a socket at each end of the reflector for each conductor, means on the back of the reflector connected at its ends to said sockets to contain the respective wires for said lamp conductors, and means connected to said first named means for containing both of said wires and for supporting the reflector from a support.
35. The combination with a reflector and an incandescent electric lamp carried thereby having lateral contacts connected with its filament at opposite ends, of sockets on corresponding ends of the reflector body in operative connection with said contacts, and a support for the reflector with circuit wires respectively led to said sockets.
40. The combination with a reflector and an incandescent electric lamp having lateral contacts connected with its filament at the ends, of sockets positioned on the reflector body opposite said contacts so as to receive the latter, and separate means located at the ends of the reflector operatively holding said sockets and contacts together.
45. An open-ended reflector composed of sections arranged in an arc of a circle, combined with a tubular incandescent electric lamp placed parallel to said sections and having uncovered ends corresponding with the open ends of the reflector, lateral conductors on the lamp leading to the opposite ends of its filament, sockets between the reflector and lamp receiving said conductors, and lamp-retaining means holding the lamp beyond said sockets.
50. The combination with a reflector and an incandescent electric lamp having laterally projecting conductors connected to the ends of its filament, of sockets opposite said conductors on the reflector body, hangers for the lamp detachably held to said sockets, and a means for supporting the reflector.
55. The combination with a suitably-supported reflector and an incandescent electric lamp therein having laterally projecting conductors connected to the ends of its filament, of sockets opposite said conductors on the reflector body, and expansible hangers on said sockets adapted to hold the lamp in position.
60. In testimony whereof I affix my signature in presence of two witnesses.
